METHOD AND MEANS FOR CAUSING SEISM
Roy W. McElroy, 1711 Ave. F, Lubbock, Tex.
Filed Sept. 18, 1958, Ser. No. 761,882
1 Claim. (Cl. 102—22)

This invention pertains to exploration of geological formations by seismic reflection etc.; and more particularly to the production of seism.

A widely used method of geological exploration includes the production of a seismic wave which bounces or echoes from a particular sub-surface formation. These echoes are recorded by seismographs and by the interpretation of the seismograms so produced; an indication may be had of the underground formation. Customarily, the seismic wave is produced by drilling a hole about a hundred feet below the surface of the earth and detonating an explosive charge within the earth.

I have invented a method of producing seism which makes it unnecessary to drill a hole within the earth. Basically, it comprises a bottom plate which rests upon the earth and a heavier weight which sets upon the bottom plate. An explosive charge is located between these two members. When the charge is detonated, an impact of large magnitude is caused upon the bottom plate forcing the earth downward, compressing it, because of the heavier upper weight.

An object of this invention is to produce seism.

Another object of this invention is to produce a single seismic wave so that seismograms may be easily interpreted.

A further object of this invention is to achieve the above with a device which is safe to operate, easy to use, and light in weight so that it is easily portable.

Still further objects are to achieve the above with a device that is sturdy, compact, simple, and reliable, yet inexpensive and easy to manufacture.

The specific nature of the invention as well as other objects, uses, and advantages thereof will clearly appear from the following description and from the accompanying drawing, in which:

FIGURE 1 is a sectional view of a device according to this invention.

FIGURE 2 is a plan view of the device shown in FIGURE 1.

As may be seen in the accompanying drawings, one embodiment of this invention uses a device having cup shaped bottom 10. This bottom member 10 has plane surfaced bottom 12 which is adapted to be set solidly upon the earth. Along the exterior of the sides of the cup shaped member are handles 14 for dragging the device along the ground.

The inside of the cup shaped member 10 has an axial cylindrical bore 16. The upper inner lip is beveled at 18 for purposes which will be described later. Concentric with the bottom is boss 20 which has rod 22 threaded into it, so that the rod 22 extends upwardly co-axial with the bottom portion. An annular concavity 24 is cut within the bottom member around the boss 20. This concavity is filled with an explosive charge 26 when the device is in use.

By means of a radial bore through the bottom member detonator 28 is introduced. It is contemplated that an electrical detonator would be used and the explosive charge be detonated with the aid of battery 30 and switch 32. As explosive charges and detonators (either electrical, mechanical, or otherwise) are well known to the art, they have not been described in detail here. The choice of the particular type of explosive to be used, the amount of the explosive charge, and the type of detonator are all well within the skill of the one ordinarily skilled in the art.

2

Upper member 34 is partially seated within the cup shaped bottom member. The upper member 34 is generally cylindrical in shape and has a reasonably snug fit with the lower member 16. The upper member has an axial bore in which the rod 22 is located. Also the upper member has an axial depression which mates with boss 20. The depth of this depression is less than the height of the boss, therefore the upper member rests upon the boss. There is a definite clearance between the bottom of the upper member and the upper portion of the bottom of the cup-shaped member. When the upper member is in the lower position as illustrated, it does not rest upon the explosive charge or any bits of the explosive charge which might be spread around. The upper member also has handles 36 by which it may be moved.

Spring catches 38 are attached to the top of the upper member. These catches are means for retaining the upper member in a separated position after the upper and lower members have been blown apart by the explosive charge. They are firmly attached to the upper member by any convenient means such as welding or bolting.

They have catch 40 at the top which is supported by leaf spring 42 which extends parallel to the axis of the device.

Loop 44 is on the extreme upper portion of the rod 22 so that a hook may be engaged therein to lift the device by power mechanism. Immediately below this loop, the rod is of greater diameter than the lower portion of the rod. This portion of greater diameter is threaded so that a stop 46 may be adjustably attached thereto. The stop 46 is a disk shaped member. The diameter of the disk is slightly greater than the distance between the catches 40 when the leaf springs 42 are in the relaxed position. Therefore as the upper member moves up, the upper surface of the catches 40 will act as cams and spread the catches apart as they move over to stop 46. However, as the upper member attempts to move downward, the lower edges of the catches will stop on the disk 46 and retain the upper member in a separated position from the lower member.

The remote ends of the catches 40 are in the form of handles 48. If it is desired to separate the upper and lower members other than by the explosive charge, the handles may be used for this purpose, preferably in conjunction with power equipment. Alternately, the disk stop 46 may be screwed down to its lowest position and the catches 40 snapped over it in this position. Then by rotating the disc along with the upper member, the upper and bottom member can be separated.

Helical compression spring 50 encircles the rod 22 and normally rests upon the top of the upper member, and extends to bottom of the stop. When the explosive charge separates the upper and lower members, the spring will produce a certain cushioning effect. With the catches preventing the upper member from falling back on the lower member, only a single impact is delivered to the earth. If the upper member were permitted to fall back on the lower member there would be two impacts delivered to the earth and two sound waves produced in it.

The first sound wave would be produced at the time of the explosive charge detonating while the second sound wave would be produced when the upper member dropped back upon the lower member.

It is necessary that the upper member have greater mass than the bottom member. Otherwise, the device would act as a launching for a projectile and the greater amount of energy would be expended in sending the upper member up. However, by making the upper member of greater mass, the greater amount of energy is expended in forcing the lower member down which gives a greater impact and seism.

The lower edge of the upper member is beveled at 52. The gases resulting from the explosion of the charge will escape in an upward manner when the bevels 18 and 52 become aligned. If it were not for these bevels, most of the gases would be dissipated in an horizontal direction. Rather good confinement of the explosion is obtained even though the top member does not fit tightly within the cup shaped member nor around the sectional rod 22. There is not a straight line escape route for the gases. The gases from the explosive charge 46 must 10 turn a corner along any route in order to escape.

With this device, a simple mechanism has been provided for producing seism. It is relatively lightweight and easily transported by a small truck. Indeed it may be transported by helicopter or blimp to extremely remote 15 areas in rough terrain making possible geophysical exploration where otherwise it would not be economically feasible to use ground vehicles.

It will be apparent that the embodiment shown is on the exemplary and that various modifications can be made 20 in construction, materials, and arrangement within the scope of the invention as defined in the appended claim.

I claim as my invention:

A means for causing seism: a rigid cup shaped bottom member, a rigid upper member seated partially within 25 said bottom member, said upper member having a greater mass than said bottom member, an explosive charge with-

in said bottom member between the two members, means for detonating the explosive charge, guide means attached to the lower member for guiding the upper member, said means for guiding including a rod extending from about the axis of the cup shaped bottom member, the upper member having a hole through which the rod extends, a stop on the rod for limiting the movement of the upper member, the stop being a disc shaped element threaded onto the rod, a helical compression spring surrounding the rod between the bottom member and the stop, and catch means attached to the upper member in operative relationship to the stop for retaining the upper member in a separated position; so that when the bottom member is placed solidly upon the earth and the charge detonated a seismic wave is produced within the earth resulting from only one impact.
